200,433

COMBINED DOOR LOCK HOUSING AND HANDLE THEREFOR

Berwyn E. Etter, 3120 46th Ave. N., St. Petersburg, Fla.

Filed Apr. 15, 1964, Ser. No. 79,615

Term of patent 3½ years

(Cl. D50—5)

I claim:

The ornamental design for a combined door lock housing and handle therefor, substantially as shown.
